L. W. KING

NECKTIE FASTENER

Filed July 14, 1921

FIG. 1.

FIG. 2.

FIG. 3.

FIG. 4.

FIG. 5.

INVENTOR

Lawrence W. King

BY
Wm. J. Davis
ATTORNEY

UNITED STATES PATENT OFFICE.

LAWRENCE W. KING, OF KANSAS CITY, MISSOURI.

NECKTIE FASTENER.

Application filed July 14, 1921. Serial No. 484,593.

To all whom it may concern:

Be it known that I, LAWRENCE W. KING, a citizen of the United States, residing at Kansas City, in the county of Jackson and State of Missouri, have invented certain new and useful Improvements in Necktie Fasteners, of which the following is a full, clear, and exact description, such as will enable others skilled in the art to which it appertains to make and use the same.

The invention relates to neck tie fasteners for equipping ties such as are commonly known as four-in-hand ties and the like, so that the tie may be connected with the folds 15 of the usual collar around the neck of the wearer and disconnected therefrom without untying the tie after it is once tied.

Most men desire to wear a four-in-hand tie, but many find it very difficult to tie, and 20 then there are those who change ties several times in a day and find that it consumes considerable valuable time to tie the tie each time it is worn.

The present invention has provided an 25 improved tie fastener that can be applied to the usual four-in-hand tie to engage it while in the collar around the neck of the wearer, so that a tie once tied will not require to be retied until it is found necessary 30 to have the tie laundered or cleaned.

A further advantage of the improved tie fastener lies in the fact that the tie will wear 35 longer and look better by dispensing with the usual tying and untying, so that the tie fastener will increase the appearance and economy of the tie.

A further advantage lies in the fact that the haberdasher from whom the tie is purchased or a friend will willingly tie the tie 40 the one time necessary for the man who desires to wear a four-in-hand tie but cannot tie it, but it would not be convenient to have it tied each time it is worn.

With these and other objects in view, the 45 invention consists in the feature of construction, combinations and arrangements hereinafter set forth and more particularly pointed out in the appended claims, the accompanying drawings illustrating the 50 improved tie fastener attached to the usual form of four-in-hand tie.

In the drawings:

Fig. 1 is a view of the improved tie fastener attached to the usual form of four-in-hand tie.

Fig. 2 is an end view of one of the tie fastener members.

Fig. 3 is a longitudinal view of the tie fastener with certain parts removed.

Fig. 4 is a longitudinal flat view of the 60 tie fastener.

Fig. 5 is a longitudinal edge view of the tie fastener.

The tie is of common and well known form and construction, and cut or otherwise 65 separated into two pieces forming the intermediate ends 2 and 3.

The tie fastener comprises members 4, 5 and 6, each of which is formed of sheet metal, the members 4 and 5 being provided 70 with duplicate means of attaching to the tie, consisting of the upturned flanges 7 extending before application to the tie, at right angles from the body 8 of the members and provided with the prongs 9 as illustrated 75 in Fig. 2, the member 5 being provided with the hook 10 as shown particularly in Figs. 3, 4, and 5.

The member 4 is provided with the hole 11 and connecting notch 12, the notch being 80 for the purpose of engaging the member 6 in locked engagement with the member 4 as shown in Figs. 4 and 5 and more fully explained hereinafter.

The member 6 is provided with the hole 85 13 to engage the hook 10 of the member 5, and with the impressed lugs 14 and 15 to hold the member in locked engagement with the member 4 as shown in Figs. 4 and 5, the lug 14 being smaller than the notch 12 90 and the lug 15 larger.

It is obvious that if the lug 14 be turned to the notch 12 the member 6 will disengage from the member 4, and if the lug 14 be reinserted in the notch 12 the members are 95 easily engaged.

The members 4 and 5 are connected with the intermediate ends 2 and 3 respectively of the tie 1 by laying the folded ends of the tie between the flanges 7 and closing 100 the flanges to a flat position as shown in Figs. 3, 4 and 5, the prongs 9 automatically being impressed in the tie and securely engaging the members to the tie.

The members 4 and 5 may be easily disengaged from the tie by bending the flanges 7 toward the position illustrated in Fig. 2, after which they may be reapplied to a different tie for use therewith.

When it is desired to wear the tie it is 110

placed around the neck of the wearer in the collar or around the usual shirt band with the hook 10 engaging the hole 13 of the member 6, and tied in the usual manner, 5 Fig. 1 illustrating the appearance of the tie when tied, and when it is desired to remove the tie it may be loosened to the position illustrated in Fig. 6 by pulling the intermediate end 3 upwardly and backwardly 10 through the knot 16, when it will be found that the hook 10 is easily disengaged from the member 6.

When the members 4, 5 and 6 and the intermediate ends 2 and 3 have been properly placed in the collar it is only necessary to grasp the knot 16 in one hand and push upwardly thereon, and at the same time pull downwardly on the end 17 of the tie to tighten it in position for wearing, the tie 20 when so placed presenting the appearance of the view Fig. 1.

The improved neck tie fastener is of chief importance in eliminating the nerve wrecking process of the frequent tying and untying of the four-in-hand tie, and will operate to enable those who cannot tie a four-in-hand to have it tied correctly once by some one who can, thus affording relief from a condition both annoying and expensive.

What I claim as new, and desire to secure 30 by Letters Patent, is:—

1. In a neck tie fastener, a fastener member formed of sheet metal and provided with a hole, an intermediate member pivotally connected in said hole and provided with an 35 engaging hole, a second fastener member formed of sheet metal and provided with a hook to engage said engaging hole, each of said fastener members provided with flanges to clamp the respective intermediate 40 ends of a two piece four-in-hand tie, and prongs on said flanges so positioned as to embed in the tie when the flanges are closed thereon.

2. In a tie fastener, a pair of fastener members each provided with means to detachably engage and connect with one of the intermediate ends of a two piece tie, one of said members provided with a hook, the remaining member provided with a round 45 hole notched at one side thereof, an intermediate member with one end thereof provided with prongs to detachably and pivotally connect in said hole and the opposite end of said member provided with a hole 50 to engage said hook.

LAWRENCE W. KING.
